US0D1025587S

(12) **United States Design Patent** (10) **Patent No.:** **US D1,025,587 S**
(45) **Date of Patent:** **** May 7, 2024**

(54) **AUTOMATED PILL DISPENSER**

(71) Applicant: **BIOCOP PRODUCTION S.A. A CONSEIL D'ADMINISTRATION, Issoire (FR)**

(72) Inventor: **Alain Marcoz**, Montmorin (FR)

(**) Term: **15 Years**

(21) Appl. No.: **35/514,381**

(22) Filed: **May 12, 2022**

(80) **Hague Agreement Data**

Int. Filing Date: **May 12, 2022**

Int. Reg. No.: **DM/220916**

Int. Reg. Date: **May 12, 2022**

Int. Reg. Pub. Date: **May 27, 2022**

(51) **LOC (14) Cl.** **03-01**

Primary Examiner — April Rivas

Assistant Examiner — Jillian Mazzola

(57) **CLAIM**

The ornamental design for an automated pill dispenser, as shown and described.

DESCRIPTION

1. Automated pill dispenser

1.1 : Front 1.2 : Back

1.3 : Top

1.4 : Bottom

1.5 : Left

1.6 : Right

1.7 : Perspective

1.8 : Perspective

The dot-dash broken lines in the figures and the lower opacity areas within the dot-dash lines, show portions of the automated pill dispenser that form no part of the claimed design.

1 Claim, 8 Drawing Sheets
